UNITED STATES PATENT OFFICE.

PHINEAS E. AUSTIN AND BYRON W. NICHOLS, OF NEW HAVEN, CONN.

SHUTTLE-CARRIER FOR SEWING-MACHINES.

SPECIFICATION forming part of Letters Patent No. 234,112, dated November 9, 1880.
Application filed February 18, 1880.

To all whom it may concern:

Be it known that we, PHINEAS E. AUSTIN and BYRON W. NICHOLS, citizens of the United States, residing at New Haven, in the county of New Haven and State of Connecticut, have invented certain new and useful Improvements in Shuttle-Carriers for Sewing-Machines; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In this invention a hood-shaped carrier, which is adapted to inclose the shuttle and which can be slid back and forth on the shuttle-lever, is attached thereto by a sleeve and is held to its place by a spiral spring. The shuttle-carrier is made so as to cover the swell of the shuttle sufficiently to keep it in position while in motion, and this construction enables the shuttle to be poised or balanced so that it will not rest its own weight against the shuttle-race. It also prevents the flying out of the shuttle if the race-covers be removed while the machine is in motion.

Referring to the accompanying drawings, Figure 1 is a bottom or under side view of the invention attached to the bed-plate of a sewing-machine of that class which is provided with a curved shuttle-race. Fig. 2 is a top view of the shuttle-driving lever with the improvement attached. Fig. 3 is a longitudinal section of the same. Fig. 4 represents a modification of the invention in which the shuttle-carrier is attached to the vibrating lever by a pin or screw passing through a slot in said lever, and the spring is coiled on a rod one end of which is attached to the screw or bolt and the other slides in a stud, as shown.

The shuttle-carrier A is attached to the vibratory shuttle-lever by a sleeve, B, and held in position by a spiral spring, C, which is coiled around the shuttle-lever and presses against the sleeve of the carrier, forcing it outward and keeping it in position against the shuttle-race.

The carrier is hood-shaped, as shown, and is constructed of metal or any other suitable material, and covers the swell or circle of the shut-

tle sufficiently to render it impossible to remove or insert the shuttle without moving the carrier away from the shuttle-race. The top side of the carrier may be cut away, as shown by dotted lines, to allow the passage of the thread around the tension-spring on the shuttle in cases where such a spring is used.

The shuttle-lever is in two parts, D D', which are clamped together by a clamp-bolt, E, as shown, so that said lever can be adjusted as to length to take up wear and regulate the tension of the spring.

The carrier is prevented from turning by a pin, d, projecting through a slot, b, in the sleeve.

In order to remove the shuttle from the carrier it is slid back on the lever, and to insert it in position for use it is only necessary to enter the point of it between the carrier and the side of the race and it is readily pressed into place, the spring allowing the carrier to recede sufficiently for the purpose and then automatically forcing it to its place.

The modification shown in Fig. 4 is adapted for machines as they are now generally made. The carrier is attached to the lever by a screw, F, which passes through a longitudinal slot, G, in the lever D, and the spring C is coiled around a rod, one end of which is secured to the screw F and the other slides in a stud or projection, H, on the lever.

Having thus described our invention, what we claim as new, and desire to secure by Letters Patent, is—

1. The combination of the hood-shaped shuttle-carrier A, provided with sleeve B, the spring C, and adjustable shuttle-lever D D', all constructed and arranged as herein set forth, for the purpose specified.

2. The combination of the shuttle-carrier A, having sleeve B, provided with slot b, spring C, adjustable lever D D', clamp pin or bolt E, and pin d, all arranged as herein set forth, for the purpose specified.

In testimony whereof we affix our signatures in presence of two witnesses.

PHINEAS E. AUSTIN.
BYRON W. NICHOLS.
